UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION SHOCK-ABSORBING MECHANISM.

Application filed December 10, 1921. Serial No. 521,298.

To all whom it may concern:

Be it known that I, JOHN F. O'CONNOR, a citizen of the United States, residing at Chicago, in the county of Cook and State of Illinois, have invented a certain new and useful Improvement in Friction Shock-Absorbing Mechanisms, of which the following is a full, clear, concise, and exact description, reference being had to the accompanying drawings, forming a part of this specification.

This invention relates to improvements in friction shock absorbing mechanisms.

The object of the invention is to provide a friction shock absorbing mechanism designed primarily for use in railway draft rigging and wherein the parts are so arranged that, during the compression stroke, the wedge is free from direct spring resistance but, at the initiation of the release action, a part of the spring resistance or reactive effort is automatically transferred to the wedge to thereby facilitate and accelerate its disengagement from the friction shoes and thus permit all of the parts being restored to normal.

In the drawings forming a part of this specification, Figure 1 is a horizontal, longitudinal, sectional view of a portion of a railway draft rigging showing my improvements in connection therewith. Figure 2 is a vertical, transverse, sectional view corresponding substantially to the line 2—2 of Figure 1. Figure 3 is a longitudinal, horizontal, sectional view, parts broken away, corresponding to Figure 1 but illustrating the condition of the parts at the initiation of the release action. Figure 4 is a vertical transverse, sectional view of the shock absorbing mechanism proper corresponding to the line 4—4 of Figure 1 and upon a somewhat larger scale. Figures 5, 6, 7, 8 and 9 are detail perspectives of the wedge, the plunger, a frame, an inner wedge, and a friction shoe, respectively, employed in my construction.

In said drawings, 10—10 denote channel draft sills of a car underframe having front and rear stop lugs 11 and 12, respectively, secured to the inner faces thereof. A portion of a drawbar is indicated at 13, the same being operatively associated with the shock absorbing mechanism proper by a hooded cast yoke 14 and coupler key 15. The shock absorbing mechanism proper and a

front follower 16 are mounted within the yoke, and the parts are sustained in operative position by a detachable saddle plate 17.

The improved shock absorbing mechanism, proper, as shown, comprises a combined friction shell and spring cage casting A; a spring resistance B; a pair of friction shoes C—C; a main wedge D; a plunger E; a spring follower F; a frame or shoe follower G; auxiliary wedges H—H; an inner central wedge J; and a retainer bolt K.

The casting A is preferably formed with a rectangular box-like shell at its front or outer end, thus providing opposed side friction surfaces 18—18, the same preferably converging slightly inwardly of the shell. Rearwardly of the friction shell proper, the casting A is made more or less cylindrical as indicated at 19 to form a spring cage 75 and centering device for the spring B, the cage portion 19 being suitably strengthened by flanges and ribs, as will be understood. The rear end of the casting cooperates with the stop lugs 12 in the manner of a rear 80 follower.

The friction shoes C are two in number and of like construction. Each is provided on the outer side thereof with a longitudinally extending friction surface 20 cooperable with the corresponding shell surface 18 and on the inner side thereof with an inclined wedge face 21. Each shoe C is also preferably provided with top and bottom horizontally extending wings 22—22, the latter however not being used as friction-generating surfaces. At its inner end, each shoe C is formed with a shoulder 23 for the purpose hereinafter described.

The wedge D consists of a heavy block 95 with an outer flat surface 24 which normally bears against the front follower 16. The main wedge D is also provided with two inwardly converging wedge faces 25—25 cooperable with the wedge faces 21 of the 100 shoes. At its inner end, the wedge D has a transverse flat face 26 and is recessed on the interior with stepped cylindrical openings 27 and 28, thus providing an outwardly facing annular shoulder 29.

The pressure-transmitting plunger E is of stepped cylindrical form having an outer section 30 and an inner section 31 of lesser diameter, thus providing an inwardly facing shoulder 32 adapted to cooperate with 110

- the shoulder 29. The plunger E is of greater length than the length of the wedge D taken parallel to the axis of the mechanism and in normal condition of the parts 5 the outer end 33 of the plunger will lie flush with the outer face 24 of the wedge at which time the annular shoulders 29 and 32 will be in engagement as shown in Figure 1.
- 10 The member G is of rectangular outline having top and bottom horizontally extending walls 34—34 and vertically extending side walls 35—35. The latter are rabbeted or cut away on the forward side of the member G so as to provide shoulders 36—36 against which the inner ends 23 of the shoes C bear, as shown in Figures 1 and 3. On their interiors, the side walls 35 of the frame or follower member G are beveled so 15 as to present rearwardly diverging wedge faces 37—37. As clearly appears from Figures 1 and 7, the member G has a sufficiently large opening 38 therethrough to freely accommodate the wedge J.
- 20 The two auxiliary wedges H are of like construction, each extending vertically and having rearwardly diverging wedge faces 39 and 40 on their forward sides and flat transversely extending faces 41 on their rear sides, the latter bearing on the spring follower F. The wedge faces 39 cooperate with the wedge faces 37 of the member G. The other wedge faces 40 cooperate with correspondingly inclined wedge faces 42—42 25 on the auxiliary wedge J. The front face 43 of the latter bears against the inner end of the plunger E.
- 25 The operation is as follows, assuming an inward or buffing movement of the drawbar 40 and starting from the normal condition of the parts as shown in Figure 1. As the drawbar and front follower move inwardly, the plunger E and main wedge D will be forced rearwardly simultaneously and uniformly therewith. During this compression stroke, it will be observed that the resistance from the spring B is transmitted in part through the wedges H and follower G to the shoes C and in part through said wedges H and the wedge J to the plunger E without any of the spring resistance being transferred directly to the wedge D. The relative positions of the friction elements remain the same during the compression stroke, the limit of which is determined preferably by the follower 16 engaging with the outer end of the casting A. Upon removal or discontinuance of the actuating force, the plunger E is relieved of 50 any substantial amount of pressure and, being freely movable within the main wedge D, is adapted to be easily projected outwardly with respect to the main wedge D. Therefore, at the initiation of the release 55 action, the friction shoes being in tight en-
- gagement with the shell and the main wedge D in comparatively tight engagement with the shoes, the first action arising under the expansion of the spring B is to force the auxiliary wedges H forwardly along the 70 outwardly converging wedge faces 37 of the member G. This movement of the wedges H in turn forces the central auxiliary wedge J outwardly, the latter encountering substantially no resistance from the plunger E 75 until finally the central auxiliary wedge J engages the inner end 26 of the main wedge D, this condition of the parts being shown in Figure 3. Not only is a part of the spring pressure thus transferred to the main 80 wedge D in what may be termed a substantially direct manner, but the action serves to give a sharp kick or jolt to the main wedge D, thus facilitating its disengagement from the shoes sufficiently to allow the 85 wedge-shoe system to collapse, all of the parts then being pushed outwardly until the plunger E is brought to rest by engagement with the front follower G when the latter is against the front stops. At this 90 point in the release action, the shoes and the wedge will continue their outward movement while the plunger E remains stationary until the condition of the parts is restored in Figure 1.
- 95 I have herein shown and described what I now consider the preferred manner of carrying out the invention but the same is merely illustrative and I contemplate all changes and modifications that come within 100 the scope of the claims appended hereto.
- I claim:
1. In a friction shock absorbing mechanism, the combination with a friction shell; of friction shoes cooperable with the shell; a spring; a wedge cooperable with said shoes; a shoe follower; and means interposed between said shoe follower and wedge cooperable to relieve the wedge of direct 105 resistance from the spring during a compression stroke and to automatically, upon discontinuance of the actuating force after a compression movement, transfer part of the spring pressure to said wedge in a direction longitudinally outward of the shell and 110 supplemental to any spring resistance transferred to the wedge through the friction shoes.
- 115 2. In a friction shock absorbing mechanism, the combination with a friction shell; of friction shoes engageable with the shell; a spring; a wedge cooperable with said shoes; a spring follower; a pressure-transmitting plunger, said plunger and wedge being arranged to directly receive 120 the actuating force from an outside follower; and means interposed between the plunger, shoes and spring follower, arranged to distribute the spring resistance to the 125 shoes and plunger independently of the 130

wedge during the compression stroke, said means, upon discontinuance of the actuating force after a compression movement, automatically shifting positions to distribute the 5 spring pressure to the wedge and shoes at the initiation of the release action.

3. In a friction shock absorbing mechanism, the combination with a friction shell; of friction shoes cooperable with the shell; 10 a spring; a wedge cooperable with said shoes; a shoe follower; a pressure-transmitting plunger, said plunger and wedge being arranged to directly receive the actuating force; and means interposed between the 15 plunger, shoes and spring arranged to distribute the spring resistance to the shoes and plunger independently of the wedge during the compression stroke, said means, upon discontinuance of the actuating force 20 after a compression movement, automatically shifting positions to distribute the spring pressure to the wedge and shoes, at the initiation of the release action, said means including a spring follower and a plurality 25 of wedges.

4. In a friction shock absorbing mechanism, the combination with a friction shell; of friction shoes cooperable with the shell; a spring; a wedge cooperable with said 30 shoes; a shoe follower; a pressure-transmitting plunger arranged to move longitudinally independently of the wedge, the plunger and wedge being adapted to directly receive the actuating force; and means interposed between 35 said follower, spring resistance, wedge and plunger operable to relieve the wedge of direct resistance from the spring during the compression stroke and arranged, upon release action, to automatically transfer part 40 of the spring pressure to said wedge in a direction longitudinally outwardly of the shell.

5. In a friction shock absorbing mechanism, the combination with a friction shell; of friction shoes cooperable with the shell; a spring; a wedge cooperable with said 45 shoes; a spring follower; a pressure-transmitting plunger arranged to move longitudinally independently of the wedge, the 50 plunger and wedge being adapted to directly receive the actuating force; and means in-

terposed between said spring follower, shoes, wedge and plunger operable to relieve the wedge of direct resistance from the spring during the compression stroke and arranged, 55 upon release action, to automatically transfer part of the spring pressure to said wedge in a direction longitudinally outwardly of the shell, said means including, a wedge follower engageable with the shoes, and a plurality of wedges interposed between the spring follower, the wedge shoe follower and the plunger.

6. In a friction shock absorbing mechanism, the combination with a friction shell 65 having interior friction surfaces; of friction shoes cooperable with said surfaces; a main wedge cooperable with said shoes; a pressure-transmitting plunger longitudinally movable a limited distance with respect to said main wedge and of greater length than the latter; a spring resistance; a wedge-shoe follower engaging the inner ends of the shoes; a spring follower; and a plurality of wedges interposed between 70 said spring follower, the shoe follower and the inner end of said plunger.

7. In a friction shock absorbing mechanism, the combination with a friction shell having interior friction surfaces; of friction shoes cooperable with said surfaces; a main wedge cooperable with said shoes; a pressure-transmitting plunger longitudinally movable a limited distance with respect to said main wedge and of greater length 85 than the latter; a spring resistance; a wedge shoe follower engaging the inner ends of the shoes; a spring follower; a central auxiliary wedge at the inner end of said plunger; and a pair of laterally and longitudinally movable wedges cooperable with said central auxiliary wedge and the wedge faces of said shoe follower, said pair of wedges engaging the spring follower.

In witness that I claim the foregoing I 95 have hereunto subscribed my name this 14th day of November, 1921.

JOHN F. O'CONNOR.
